(57) **CLAIM**

The ornamental design for a walk behind mower engine shroud, as shown and described.

DESCRIPTION

FIG. 1 is a front perspective view of a walk behind mower engine shroud showing our new design in use condition;

FIG. 2 is an enlarged front perspective view thereof;

FIG. 3 is a top plan view thereof;

FIG. 4 is a right side elevation view thereof;

FIG. 5 is a left side elevation view thereof;

FIG. 6 is a front elevation view thereof; and,

FIG. 7 is a rear view thereof.

The broken lines shown in the drawing figures are for the purpose of illustrating environmental structure and form no part of the claimed design.
